US00D752574S

(12) **United States Design Patent**
Lam et al.

(10) **Patent No.:** **US D752,574 S**
(45) **Date of Patent:** **** Mar. 29, 2016**

(54) **NOTEBOOK COMPUTER HOUSING**

(71) Applicant: **Google Inc.**, Mountain View, CA (US)

(72) Inventors: **Lawrence Lam**, San Jose, CA (US);
Joseph Edward Clayton, San Francisco,
CA (US)

(73) Assignee: **Google Inc.**, Mountain View, CA (US)

(**) Term: **14 Years**

(21) Appl. No.: **29/512,394**

(22) Filed: **Dec. 18, 2014**

Related U.S. Application Data

(62) Division of application No. 29/458,377, filed on Jun.
19, 2013, now Pat. No. Des. 722,314, which is a
division of application No. 29/408,679, filed on Dec.
15, 2011, now Pat. No. Des. 684,964.

(57) **CLAIM**

The ornamental design for a notebook computer housing, as
shown and described.

DESCRIPTION

FIG. 1 is a bottom-front perspective view of a notebook
computer housing shown in a closed configuration according
to our design;

FIG. 2 is a top view thereof;

FIG. 3 is a bottom view thereof;

FIG. 4 is a front side view thereof;

FIG. 5 is a back side view thereof;

FIG. 6 is a right side view thereof;

FIG. 7 is a left side view thereof;

FIG. 8 is a top-front perspective view thereof in an open
configuration;

FIG. 9 is a top view thereof;

FIG. 10 is a bottom view thereof;

FIG. 11 is a front side view thereof;

FIG. 12 is a back side view thereof;

FIG. 13 is a right side view thereof; and,

FIG. 14 is a left side view thereof.

Broken lines are environmental only and form no part of the
claimed design.

1 Claim, 14 Drawing Sheets
